UNITED STATES PATENT OFFICE.

FREDERICK SCHWANHAUSSER, OF NEW YORK, N. Y., ASSIGNOR TO RUSLING WOOD,
OF NEW YORK, N. Y.

MOUNTING.

Application filed May 6, 1921. Serial No. 467,231.

To all whom it may concern:

Be it known that I, FREDERICK SCHWANHAUSSER, a citizen of the United States, and a resident of the city of New York, borough 5 of Manhattan, county of New York, and State of New York, have invented a new and Improved Mounting, of which the following is a full, clear, and exact description.

10 My invention relates to a mounting, and aims to provide certain new and useful improvements in connection with a device of this character, and more particularly a mounting which is adapted to support a projecting machine.

It is well appreciated by those conversant with projecting apparatus such as is utilized in billposter work, that considerable difficulty has been experienced incident 20 to vibration. This difficulty is to be predicated to the fact that in projecting an image upon a surface adapted to receive the same, which projection must usually be continued for a relatively long period, that a 25 minute amount of vibration transmitted to the projecting apparatus will result in a very perceptible movement of the image upon the surface. This will result in a blurred appearance of all lines and in the finished 30 work, an "overlap" will be noted which in many instances calls for the entire work being rejected necessitating its duplication.

Thus it is necessary that the projecting apparatus and receiving surface be held as 35 nearly immovable with respect to each other as possible to avoid defective work, and to reduce the cost of manufacture.

Having this in mind, I have constructed a mounting which may be disposed upon a 40 supporting surface, which is subject to the usual amount of vibration, but which mounting will incorporate structure capable of absorbing to the greatest degree all shocks, and tremors so that the projecting apparatus 45 and image receiving surface to be held is as nearly immovable as possible, thus overcoming the difficulty aforementioned.

A further object of my invention is the construction of a device of the nature specified, the parts of which shall be capable 50 of being manufactured at a relatively low figure, aside from the fact that the cost of maintenance will be virtually negligible.

Further objects of my invention will appear in the annexed specification taken in

connection with the drawings which latter present one practical embodiment of the same, and in which:

Figure 1 is a partly fragmentary side view of a mounting constructed in accordance with my invention and showing the same supporting a projecting apparatus and receiving surface of any desired design. 60

Figure 2 is a plan view thereof.

Figure 3 is an end view of the same, and 65

Figure 4 is a sectional view taken along the line 4—4 and in the direction of the arrows indicated in Figure 3.

It will be noted in these views, that the reference numeral 5 indicates the screen or 70 image receiving surface of any desirable type, and the reference numeral 6 the projecting apparatus mounted upon the carriage 7, the said projecting apparatus serving to permit of the production of light rays which 75 are thrown against the screen 5.

Now with a view of providing means which will serve to guard against any vibration being transmitted from the supporting surface 8 to the apparatus comprising the 80 elements 5 and 6, it will be noted that the support includes a pair of base members 9 resting upon the surface 8. These members have arms 10 attached to their bodies adjacent their outer ends, and these arms extend upon opposite sides of a bridge 11 of any desirable type, to the upper surface of which tracks 12 are secured mounting the carriage 7. 85

In connection with the bridge 11 it is to 90 be noted that the same may be of any desirable construction, as long as it incorporates rigid qualities preventing any sway or distortion on the part of its body incident to movement of the carriage 7 over the rails 95 12, which is necessary to secure the desired degree of enlargement.

Further each of the arms 10 terminates in an inwardly bent portion 13 overlying the base 14 of the bridge 11, and springs 15 100 extend between and have their ends secured respectively to the outer ends of the arms 10, and the base 14 of the bridge 11 whereby to support the latter.

Further springs 16 also extend between 105 the bridge 11 and arms 10, but it is to be noted that these latter springs have their bodies arranged in a plane transverse to that in which the springs 15 lie thus the springs 15 serve as retaining elements to 110

prevent shocks in a vertical plane being transmitted from the base members 9 to the bridge 11, while the springs 16 guard against lateral movement of the bridge with respect to the supporting members.

From the foregoing it will be noted that I have provided a mounting which will serve to support the entire apparatus necessary for enlargement work, in such a manner that the parts of the same will be held immovable with respect to each other, although movement will be permitted with respect to a main supporting surface incident to the fact that vibrations received by the said main supporting surface will be absorbed to a maximum extent by the mounting, and thus fail to be transmitted to the apparatus whereby to eliminate the objections incident to this difficulty, as has been noted in the preamble of this specification.

Obviously numerous modifications of structure might readily be resorted to without in the least departing from the spirit of my invention which I claim as:

25 1. A support, including supporting members, a bridge, arms secured to said supporting members, a plurality of springs secured to said arms, and having their opposite ends secured to said bridge, said springs being arranged transversely with respect to each other.

30 2. A support, including a bridge, a base forming a part of said bridge, supporting members, arms secured to said supporting

members, springs extending between and 35 having their opposite ends secured to said arms and bridge respectively, certain of said springs being attached to the base of said bridge and arranged transversely with respect to the other springs.

3. A support, including supporting members, arms secured to said supporting members, a bridge, a base forming a part of 40 said bridge, the outer ends of said arms being bent inwardly and overlying the side edges of said base, springs extending between and having their ends secured respectively to the outer ends of said arms and side edges of said base, and further springs extending between and having their ends secured to the bridge proper and body of the 45 arms respectively.

4. A support, including supporting members, arms secured to said supporting members, a bridge, a base forming a part of 50 said bridge, the outer ends of said arms being bent inwardly and overlying the side edges of said base, springs extending between and having their ends secured respectively to the outer ends of said arms and 55 side edges of said base, and further springs extending between and having their ends secured to the bridge proper and body of the arms respectively, said latter springs extending transversely with respect to said 60 first named springs.

F. SCHWANHAUSSER.
